UNITED STATES PATENT OFFICE.

WILLIAM EVANS, OF PROVIDENCE, RHODE ISLAND.

CROSS-WEAVING MECHANISM.

SPECIFICATION forming part of Letters Patent No. 364,402, dated June 7, 1887.

Application filed May 14, 1886. Serial No. 202,141. (No model.)

To all whom it may concern:

Be it known that I, WILLIAM EVANS, of the city and county of Providence, and State of Rhode Island, have invented certain new and useful Improvements in Cross-Weaving Mechanisms, of which the following is a full, clear, and exact description, reference being had to the accompanying drawings, forming a part of this specification.

10 My invention relates to cross or gauze weaving mechanism and to the double-acting or open-shed class of looms.

The objects of my invention are to provide an efficient and comparatively simple mechanism for cross or gauze weaving, and to adapt the class of fancy or open-shed looms to weave the peculiar kind of fabrics known as "gauze" and "lineau" or "leno." As is well known, the fabric gauze differs, essentially, from all other fabrics, in that in a pair of contiguous warp-threads one of said warps always lies to the upper side and the other lies to the under side of the interwoven weft-threads throughout the weaving. This characteristic is due to the peculiar twist of the pair of contiguous warps upon themselves between any two consecutive picks of the shuttle. These twists of the warps are from right to left and left to right alternately, so that the one warp is maintained to the one side and the other warp to the other side of the weft, which is laid after every twist, and thus is formed a succession of loops of the warps having these twists interposed and the wefts interwoven in said loops. The fabric called "lineau" or "leno" is composed of the combination of the above-described gauze-weave and any other form of weaving—as, for instance, the plain weaving, in which the warps are crossed X-shaped, in contradistinction to the twisting of the gauze-weaving.

In the operations of weaving gauze and lineau the conditions require that, of a pair of contiguous warps to be twisted and interwoven with wefts, if one of said warps be raised and the other depressed to form the shed for the shuttle to pass through, the raised warp must be passed under the depressed warp and raised again before the next pick of the shuttle. Heretofore these fabrics have been made only on the single-acting gauze-looms, which level

all warps at every pick of the shuttle, and at the leveling point cross the warps to effect the twist. Thus, prior to my invention, these fabrics have been woven under all the deficiencies of the single-acting loom compared with the double acting loom. As is well known, the most important advantage of the double-acting over the single acting loom is the increased speed at which it can be operated. This gain of speed is owing to the ability of the double-acting loom to select and withhold certain warps for a certain number of succeeding picks of the shuttle, as the pattern being worked may demand. However, the construction of the double acting loom heretofore employed did not permit of its weaving gauze and lineau, because of the inability of the loom to operate a warp-thread so as to raise it for one pick of the shuttle, and then, after that pick, lower it and raise it again before the succeeding pick of the shuttle. It is one purpose of my invention to overcome this defect and to adapt this class of looms to weave gauze and lineau with their usual speed, and at the same time to in no wise incapacitate the loom in performing its ordinary work.

My invention essentially consists in combining the ordinary full motions of the recurrent or reciprocating harnesses with a novel and peculiar half-and-return motion of others of the harnesses; and, further, my invention consists in the new constructions and arrangements of certain necessary parts, as hereinafter fully described and claimed.

I have here merely illustrated my invention as embodied in and co-operating with the class of looms known as the "dobby," in which the harnesses are lifted by a positive action of jacks and lifters, and subsequently depressed by retracting-springs or by weights. Of this character of the dobby-loom a full description with illustrations may be found in United States Letters Patent for a loom, No. 217,589, dated July 15, 1879.

In the accompanying drawings, illustrating my invention, Figure 1 is a rear view of the head or end of the loom containing the harness-operating mechanism, the main part of the loom being omitted. Fig. 2 is a view of my double-hooked jack detached. Figs. 3, 4, 5, and 6 are diminished perspective views of the

harnesses and operating-levers and connecting cording with their guide-pulleys. These views represent the harness-frames and levers in portions, and show four succeeding positions of several parts in Fig. 1, as hereinafter fully described.

In the said drawings, like letters and numbers designate corresponding parts throughout.

10 I will first describe the well-known parts of the shedding mechanism as used in the above-referred-to patent, and will then proceed to set out my invention.

Referring to the said drawings, the frame 10 forms the head or structure of the loom containing the shedding mechanism and adjuncts. The main cog-wheel 11 receives motion suitably from the counter-shaft, (not shown,) and thereby reciprocates the connecting-rod 12, 20 joined to the crank-pin 13 by means of an ordinary knuckle-joint. The upper end of rod 12 is attached by a pivot to the stem or main arm of the T-shaped rocker 14, keyed on shaft 15, which is journaled in frame 10. The ends 25 of the cross-head of rocker 14 are each fastened by means of a pivot-joint to a hook, 16, which are fixed, respectively, to the lifters 17 and 18, sliding horizontally in the slots 19, formed in frame 10. Some of these described 30 parts are repeated upon the other or front side of the loom, and operate similarly to give an even motion.

The harness-operating lever *d* has a straight head with a series of notches, 21, thereon, for the regulation of the harness-cording *d'*, which passes over guide-pulley 23, and is fastened to the frame *D*. The operations of lever *d* serve to elevate the harness-frame *D*, which is depressed by the force of the retracting-spring 35 40. The lower and outer end of operating-lever *d* has a notch, 26, riding on the fulcrum-rod 27, with which it is kept in close engagement by means of the curved slot 28, working on bar 29. Near the center of lever *d*, and in 45 an extension thereof, is arranged a notch, 30, into which takes loosely the pin 31, fixed near the central point of the connector 32, which vibrates on said pin. To the lower end of connector 32 is fastened, by means of a pivot, 50 the jack 33, provided with a hook, 34, located at the outer end, and designed to engage the lifter 18. To the upper end of connector 32 is similarly affixed the jack 35, provided with the hook 36, engaging with lifter 17. In an 55 obvious manner the connector 32 may be made to rest with both its upper and lower ends against the fulcrum-points 37 and 38, respectively, or with its lower end against point 38, as shown, or with its upper end on point 37. 60 The needle or jack selector 40 is set through guide-pieces 41, and also passes through longitudinal slots in the jacks 33 and 35, and carries near the upper and lower ends the fixed collars 42 and 43, which take up against the 65 under sides of said jacks. The lower end of selector 40 rests upon the inner end of the trip-lever 44, pivoted at 45, and the outer end

of which is tripped by the elements or pins on pattern-chain 46, which is passed thereunder by the revolving chain-cylinder 47.

When the cog-wheel 11 revolves, it reciprocates rod 12, which vibrates rocker 14, which turns with its shaft 15, and this serves to reciprocate the lifters 17 and 18 horizontally in their slots. While a jack is in engagement 75 with an outgoing lifter, the jack follows it and draws outward the corresponding end of connector 32, which carries in like manner operating-lever *d*, and so lifts the attached harness. The selector 40 is controlled indirectly by the 80 pattern-chain 46, and selects the jacks to engage with or miss the traveling lifters and to operate the harness, according as the elements of the pattern demand. In the positions shown the lifters 18 and 17 may be supposed 85 as having reached about the midway point of their traverse—the former on an inward and the latter on an outward traverse. The jack 35 being in engagement with lifter 17 and the jack 33 out of engagement with lifter 18, the 90 connector 32 is bearing on fulcrum-point 38, and is drawing lever *d* outward and lifting the connected harness. Thus in a well-known manner the jacks are controlled indirectly by the elements of the pattern to operate the 95 harness.

I will now consider the description and operations of my improvements and their co-operation with the above-described ordinary features of a shedding mechanism.

By my invention I secure a peculiar half-and-return motion of certain harnesses, combined with certain full motions thereof, when so desired. To gain the half-and-return motions I have shown an extra half-stroke lifter, 105 which has half the limit of traverse that the ordinary lifters have. The half-stroke lifter has suitable jacks engaging therewith, which may be joined in the usual way with a connector co-operating with an operating-lever. 110 The half-stroke lifter I reciprocate by a peculiar half-motion device, hereinafter described. I obtain a second half-and-return motion of certain other harnesses by the arrangement of 115 a pair of ordinary operating-levers with connections to a single harness controlled by the levers working simultaneously and oppositely or singly. All of these parts are adapted to be used with any suitable patterns for weaving gauze and lineau.

In the drawings the four harnesses *A* *B* *C* *D* are represented as being operated by five levers, *a* *a'* *b* *c* *d*, which serve to elevate their respectively-connected harnesses, which are subsequently depressed by virtue of the retracting-springs 25, secured one upon the bottom of each harness-frame in a well-known manner. The harnesses lie one back of the other, so that in the view of Fig. 1 only the retracting-spring 25, connected to harness *D*, 125 is seen. The two-armed or L-shaped rocker 50 is keyed upon the end of the shaft 51, loosely mounted in frame 10, and extending from back to front of the frame. The lower

arm of rocker 50 is connected by a knuckle-jointed link with the connecting-rod 52, which has its other end attached to the crank-pin 53 of gear 54, in mesh with cog-wheel 11. The 5 extra or half-stroke lifter 55 is constructed and reciprocates like the lifters 17 and 18. The lifter 55 works in the slot 56 and a corresponding slot on the front of the frame formed similarly to slot 56 by means of a bracket, 57, and 10 frame 10. The half-stroke lifter 55 is attached to the upper arm of rocker 50 by means of hook 58, and has its remote end at the front of the loom connected similarly to an arm keyed upon the front end of shaft 51. These 15 extra parts of my improvement are duplicated at the front of the loom-frame, where necessary, as in the case of the above described old features, and this for the like reason of giving a more uniform and steadier motion to the 20 working parts.

Instead of using a separate and individual jack with an upwardly-extending hook to engage with the extra half-stroke lifter, I employ an equivalent therefor, as shown in Fig. 25 2. The jack 20 is longer than the other ordinary forms of 33 or 35, and is provided with a downwardly and upwardly projecting hook, 22 and 59, respectively. Considered with its hook 22, the jack is equivalent to the old form, 30 and by extending the jack in length and adding the hook 59, I merge the two required jacks into one. The hook 59 coacts with half-stroke lifter 55 in the manner described for the full-stroke lifters 17 and 18 and their jacks.

35 The gear 54 is one-half the circumference of main cog 11, and makes two revolutions to one of the cog. It is evident that the half-stroke lifter 55, operated by gear 54, will reciprocate in its slots one-half the distance 40 traversed by the full-stroke lifters 17 and 18, which are operated by cog 11. While a full-stroke lifter makes its complete one-way traverse, the half-stroke lifter, traveling half the distance, will make its complete one-way traverse and return. This half stroke of lifter 55 is transmitted to the operating-lever *c* by 45 means of hook 59 on the jack 20, which governs said lever, and the connected harness-frame *C* is thereby given a half-motion by 50 jack 20 and returned by the ordinary retracting-spring connected at the bottom of said frame.

I show the double-hooked jack 20 as influenced by three different lengths of elements 55 in the pattern-chain 46—namely, a long pin, a short pin, and the lack of a pin, or the bare pattern-chain bar. As afterward explained, this is for weaving a linea fabric, and the jack 20, in consequence of the three-sized elements of the pattern, may assume three different positions relative to the half and full stroke lifters 55 and 17, respectively. Under 60 the conditions shown, the pattern-chain bar in the pattern-chain has permitted the elevation 65 of the inner end of the trip-lever 80, and accordingly the jack-selector coacting with jack 20 is at its highest position, and engages lifter

55. When the next element, a short pin, 61, is passed under the trip-lever, the jack 20 will be in its second position, and both its hooks 70 59 and 22 will clear the half and full stroke lifters 55 and 17, respectively. When the third element of a long pin, 60, of the chain 46 is presented to the trip-lever, the jack 20 will accordingly assume its lowest position, and 75 hook 22 will engage lifter 17.

I obtain the second half-and-return motion of the desired harness by virtue of arranging a pair of operating-levers, *a' a²*, in connection with a single-harness doup staff, *A*. The operations of the half-stroke lifter and the half-motion levers *a' a²* are disconnected; but their results co-operate to effect the conditions hereinafter described. Considering a single operating-lever as operating a single harness and 85 the lever as governed by jacks coacting with full-stroke lifters, if one of said jacks engage a lifter for a complete one-way traverse, the harness will accordingly respond, and the lever by its sole action can only transmit whatever 90 motion may be given to it. Now, considering a single harness, as *A*, connected with a pair of operating-levers, *a' a²*, both coacting with full-stroke lifters, in this case, when the levers are both at the half-way point of their movements, their cordings connecting with harness *A* are alike taut. When, however, they move oppositely, *a²* inwardly and *a'* outwardly, to their limits, the connection with *a²* is slack and the one with *a'* taut, because it alone will 95 have the weight of the attached harness. When they move back again in this alternate manner, at the midway and passing point the lever *a²* will at that point take up the weight of the harness, and will halve the motion and 100 return the harness to starting-point. In this manner of simultaneously operating these levers oppositely, they may be continuously operated to impart a half-motion to the single connected harness. I show the levers *a' a²* as 105 arranged with a Y-shaped strap, *R*. These levers may each one also serve to impart a full motion to the connected harness, by virtue of either one of them being moved from inward to outward limit, while its fellow lever remains stationary. These levers I call the 110 "half-motion" levers, because they are capable of giving a half-motion in any desired consecutive number of times when operated oppositely and simultaneously, as above described. 115

Fig. 1 represents the full and half stroke lifters as at their midway points of travel, and the coacting jacks and conjoined parts accordingly in their relative positions. The operating-levers *a' a² b c* are all provided with connectors and suitable adjuncts, like those described for lever *d*, except the double-hooked jack 20 for the lever *c*, and the forked connection *R*, for levers *a' a²*. 130

In Fig. 1 the lever *a²* is at the inward limit of travel, with its fork of connection *R* slack, since its fellow lever, *a'*, is moving outwardly on the full stroke lifter 17, by virtue of a long

pin on chain 46. The lever *b* is at the midway point, falling inwardly, by virtue of a short pin having thrown its jack out of engagement by tripping the lever 71. The lever 5 *c* is at the midway point of its half-motion, by virtue of the pattern-chain bar of chain 46 having dropped its trip-lever 80 to the lowest point. The position of lever *d* has been before described. The connectors 76 and 77, attached to the jacks 74 and 20, respectively, are connected with their respective levers *a*² and *c*. The several harness frames A B CD are at the midway points of their reciprocations.

Figs. 3, 4, 5, and 6 illustrate four successive 15 relative positions of the harness and harness-operating levers as they occur in the weaving of lineau according to the manner and pattern here shown. The parts designated D and C are portions of ordinary harness-frames provided with single-eyed heddles carrying the warps *m* and *n*, respectively. These frames are connected by the respective cordings *d* and *c*, passing oversuitable guide-pulleys, with their operating-levers *d* and *c*, the former 20 acting with full-stroke lifters, and the latter with my full and half stroke lifters.

The standard or doup frame B (shown in portion) is an ordinary harness-frame provided with a double-eyed or doup heddle, through 25 each eye of which passes one side of the looped cord or doup *k*, the ends of which are attached to the doup-staff A. The doup-frame B is suitably connected with lever *b* by means of cording *b'*, and coacts with full-stroke lifters. 30 The doup-staff A (shown in portion) is operated by the half-motion levers *a'* *a*², to which it is connected by the Y-shaped connecting strap R, both forks of which are equal and connected, one with each lever *a'* *a*², respectively, and its stem is connected with the staff A. The parts of harness A, B, C, and D are represented as located, one back of the other, in the order enumerated, A being at the front. By the constructions described the harness-frames B and D make full straight-away motions, while the parts A and C make half-and-return motions, and are also capable of making full straight-away motions. These parts are thus termed, the former "full-motion" 45 and the latter "half-and-return-motion" harnesses.

It is to be observed that in Figs. 3, 4, 5, and 6 the ordinary retracting-springs, shown in Fig. 1 are in these views omitted. However, 50 the necessary office of these springs will be readily understood by one familiar with the art. The term "harness-frame" is employed to designate the loom-harness comprising the laths and the heddles mounted thereon. 55 The warps *m* and *n*, I term the "upper" and "under" warps, respectively, because in the gauze-stitches of the weave they are located to the upper and under sides of the interwoven weft. In drawing in these warps in their respective harness-eyes the under warp, *n*, merely passes through its harness-eye, and is maintained in a straight path, while the upper

warp, *m*, is set in its harness eye, and is also passed through the doup *k*, so that at times it will be thereby drawn aside from its straight path and crossed upon the heddle bearing the under warp, *n*.

In describing the positions of the recurrent or reciprocating harness frames, according to the pattern shown for weaving a simple design of lineau fabric after my method, I will designate the three situations of the harnesses at their highest, middle, and lowest points of reciprocation as the "high limit," "midway point," and "low limit," respectively. The 75 harness C, carrying the under warp, *n*, is given the half-and-return motion in order to carry the warp *n* to the midway point, where the descending warp *m* can be passed under warp *n*, which then descends, while the doup *k* raises 80 warp *m* to form the upper part while the warp *n* forms the lower part of the shed for the next pick of the shuttle.

Referring to Fig. 3, let it be supposed that the position there illustrated is the first position before starting the loom, which may be supposed to have been previously making gauze stitches, and which came to rest while the warps were partly turned on themselves for the next twist. In this position all the harnesses, A, B, C, and D, are at the low limit, and the upper and under warps, *m* and *n*, are leveled and crossed one above the other, preparatory to being twisted on themselves in the formation of the succeeding gauze-stitch. The levers *a'* *a*² *b* *c* *d* in this first position are all in line and the branches of the forked connection are both taut. The condition of the second relative position of Fig. 4 is produced by the levers *a'* and *a*² moving to the outward limit on full-stroke lifters and the levers *a*² *b* *c* remaining at rest. This serves to raise harness A and D from low to high limit. By this shedding movement the crossed warps have been tightly twisted on themselves, and the shuttle

90 95 100 105 110 115 120 125 130 here makes a pick through the shed and interweaves the weft between the twisted warps. The next and third position in Fig. 5 is obtained by levers *a'* and *a*² moving oppositely on full motions—one on a lifter and the other by a retracting-spring, as above described—and thereby giving their doup-staff A a half-and-return motion; also, by lever *b* moving outwardly on a full-stroke lifter, and accordingly moving the doup-frame B from low to high limit; also, by lever *c* coacting with the half-stroke lifter and imparting a half-and-return motion to its frame C; also, by the lever *d* moving inwardly a full motion by means of a retracting-spring, and imparting a like motion to its upper warp-frame, D, which moves accordingly from high to low limit. During this change of position the warps have been crossed and twisted on themselves, forming a gauze-stitch, and then the shuttle picks and lays the weft. The next and fourth position of Fig. 6 is arrived at by levers *d* and *a'* remaining at rest, while *a*² and *b* are moved in by virtue of their respective retracting-springs, and *c* is

carried out on a full motion by virtue of its jack 20 coacting with a full-stroke lifter. These movements have caused the doup-frame and staff A and B to descend from high to low 5 limit, frame C to rise from low to high limit, and frame D to remain at rest at low limit. In this change of position the warps have not been twisted, but merely crossed side by side, as in plain weaving, and in this position of 10 Fig. 6 the shuttle picks and interweaves the weft. This position now changes the position of the upper and under warps reversely relative to the weft. From the position of Fig. 6 the changes may be made, according to the 15 pattern desired, into a series of succeeding similar positions, and thus make more plain weaving-strokes, or it may be changed back to the second position of Fig. 4 and repeat the described pattern of lineau.

20 It is obvious that the design of the lineau-pattern may be varied at pleasure, and the half-motion harnesses will accordingly make any number of succeeding full straight-away motions and half-and-return motions alternately. For instance, the pattern may call 25 for three succeeding full straight-away motions of the half-motion harnesses to make plain stitches, and then alternate to two half-and-return motions of the same harness to 30 form gauze or twisted stitches. To weave a continuous gauze fabric the half-motion harness would be controlled by the pattern to make half-motions successively. Considering 35 the case when the fourth position of Fig. 6 is changed to the second position of Fig. 4, and so repeated, a lineau fabric will be constructed of twisted and crossed stitches combined in two of the former and one of the latter alternately throughout. The different positions of 40 the harness and operating-levers illustrated in Figs. 3, 4, 5, and 6 represent the extreme limits of movement of these relative parts.

By virtue of my described improvements of combining the half and full motions of certain of the loom-harnesses I can readily operate the ordinary fancy or double acting loom to weave gauze and lineau fabrics in a rapid and efficient manner, and any pattern of lineau can be constructed by the use of my invention. This is due to the fact that by the combination of the motions described the double-acting loom is adapted to raise a warp for one 50 pick of the shuttle, and then after that pick lower it and raise it again before the succeeding pick of the shuttle. I secure all the advantages of a double-acting over the single-acting loom in weaving gauze and lineau, and can therefore in a given time weave more fabric than the single-acting loom. I obtain the 55 same uniformity of speed in the motion of the threads throughout, since all threads pass the same distance in the same time, and only at the time the worked pattern demands. Any number of the sets of half and full motion combinations of harnesses may be used and may be combined at pleasure to vary the patterns.

My invention does not in any respect retard or alter the operations of the double-acting loom, and can readily be thrown out 70 or in operation, as required.

There may be various modifications made in the several parts of the apparatus shown without a substantial departure from the spirit of my invention, as herein described and 75 claimed.

Having thus described my invention, I claim as new and desire to secure by Letters Patent—

1. In combination, a harness-frame, a pair 80 of operating-levers for said frame, and connections between said frame and levers, whereby said levers may together or alternately operate said frame.

2. In combination, a harness-frame, a pair of 85 operating-levers for said frame, and a Y-shaped or equivalent connection having the stem thereof attached to said frame and the branches thereof attached one to each of said levers, respectively, whereby said levers may operate 90 said frame on a full straight-away motion or on a half-and-return motion.

3. In combination, a harness-frame and a connected operating-lever therefor, provided 95 with a connector and jacks, the loom-frame lifters engaging said jacks, means for operating said lifters different distances, as described, means for throwing in or out of engagement said jacks and lifters, whereby said frame may move accordingly on a full straight-away 100 motion and a half-and-return motion alternately, or may move solely and successively on either of said motions.

4. In combination with the loom-frame and reciprocating full and half stroke lifters, first, 105 a pair of harness-frames and connected operating-levers therefor, provided with connectors and jacks; second, a harness-frame and a connected operating-lever therefor, provided with a connector and jacks; third, a harness-frame and a pair of operating-levers connected therewith and provided with connectors and jacks; fourth, means for throwing in and out of engagement all of said jacks and lifters, and means for actuating said lifters, whereby 115 the pair of said first frames may move on full straight-away motions, and said second and third frames may move any number of times on full straight-away motions and half-and-return motions alternately, or on either of said 120 motions successively.

5. In combination, a harness-frame carrying an upper warp, a harness-frame carrying an under warp, a doup frame and doup-staff together carrying a doup, said upper warp 125 passed through said doup and controlled thereby, the loom-frame and half and full stroke lifters, means for reciprocating said lifters, the operating-levers, the forked strap, connections between the said harness-frames, 130 doup frame and staff, and the operating-levers and forked strap, the connectors and jacks, the jack-selectors and trip-levers, and the pattern-chain, all constructed and arranged for

operating said upper warp and doup frames on full straight-away motions, and for operating said under warp-frame and doup-staff on any number of full straight-away and half-and-
5 return motions alternately, or on either of said motions successively.

6. In combination with the loom-frame and reciprocating half and full stroke lifters, a harness-frame carrying an upper warp and provided
10 with a connected operating-lever and a connector and jacks governing said lever and coacting with the full-stroke lifters, a harness-frame carrying an under warp and provided with a connected operating-lever and a connector and jacks governing said lever and coacting with both the full and the half stroke lifters, a doup-frame and doup-staff together carrying the doup, said upper warp passed through and controlled by said doup, said
15 doup-frame provided with a connected operating-lever and a connector and jacks governing said lever and coacting with the full-stroke lifters, said doup-staff provided with a pair of operating-levers connected therewith, connectors and jacks governing said levers and coacting with the full-stroke lifters, means for actuating all of said lifters, and means for throwing in or out of engagement said jacks and lifters, whereby said upper warp and
20 doup frames may move on full straight-away motions and said under warp-frame and doup-staff may each move any number of times on full straight-away and half-and-return motions alternately, or on said half-and-return
25 motions successively.

7. In combination with the loom-frame, a T-shaped rocker and full-stroke lifters actuated thereby, an L-shaped rocker and a half-stroke lifter actuated thereby, one or more sets, consisting of two harness-frames carrying the upper and under warps, respectively, a doup-frame and a staff together carrying the doup, one or more sets of five operating-levers connected with said harnesses, having a pair
40 of every said five connected with a doup-staff, connectors and jacks, jack-selectors for said jacks, means for controlling said selectors, and means for actuating said rockers, whereby the said sets of harnesses may be moved in pairs—
45 the one pair on full straight-away motions, the other pair on any number of full straight-away and half-and-return motions alternately, or on either of said motions successively.

8. In combination with the loom-frame, the full-stroke lifters and the half-stroke lifter and actuating means therefor, an upper-warp full-motion harness-frame and a full-motion doup-frame, each of said frames provided with a connected operating-lever and a connector and jacks governing said lever and coacting with said full-stroke lifters, a half-and-return-motion under-warp frame, provided with a connected operating-lever and a connector and jacks governing said lever and coacting with
55 said half-stroke lifter, a half-and-return-motion doup-staff, together with said doup-frame, carrying a doup and provided with a pair of

connected operating-levers and connectors and jacks governing said levers and coacting with said full-stroke lifters, a pattern-chain provided with three different elements, and means intermediate between said pattern-chain and jacks.

9. In combination with the loom-frame, the full and the half stroke lifters and actuating means therefor, a full-motion harness-frame, carrying an upper warp and provided with a connected operating-lever and a connector and jacks governing said lever and coacting with said full-stroke lifters, a half-and-return-motion harness-frame carrying an under warp, and provided with a connected operating-lever and a connector and jacks governing said lever and coacting with said full and half stroke lifters, a full-motion doup-frame carrying the doup and provided with a connected operating-lever and a connector and jacks governing said lever and coacting with said full-stroke lifters, a half-and-return-motion doup-staff, also carrying the doup and provided with a pair of connected half-motion operating-levers and connectors and jacks governing said levers and coacting with said full-stroke lifters, a pattern-chain provided with three different elements, means intermediate between said pattern-chain and jacks, said elements prearranged to operate in order upon said intermediate means and select the jacks, whereby said upper and under warps may be twisted on each other and crossed by each other alternately any number of predetermined times, as set forth.

10. The combination, with the loom-frame and the half and full stroke lifters, and means for actuating the lifters, of the jack provided with two oppositely-disposed hooks, the connector and operating-lever, the jack-selector, the trip-lever, and the pattern-chain having three different elements therein, whereby said jack may have three distinct positions relative to said lifters, substantially as described.

11. In combination with the loom-frame, the full-stroke lifters, the T-shaped rocker provided with connecting-hooks and reciprocating said lifters, the stem of said rocker provided with a connecting-rod, the main cog-wheel, to which said rod is secured by a crank-pin, the half-stroke lifter, the L-shaped rocker provided with a connecting-hook and reciprocating said half-stroke lifter, a connecting-rod secured upon said L-shaped rocker, and a gear-wheel connected therewith, said gear-wheel in mesh with said cog-wheel and one-half the circumference thereof, the harness-frames, doup-frame, and doup-staff, the connected operating-levers and the forked connection, the connectors and the single and double hooked jacks, the jack-selectors and trip-levers therefor, and the pattern-chain engaging said trip-levers, all substantially as and for the purpose herein described.

12. The combination, with the loom-frame, of the full-stroke lifters 17 and 18 and the half-stroke lifter 55, and means for operating said

lifters, the doup-staff A and the doup-frame B, together provided with the doup *k*, the harness-frames C and D, the operating-levers *a'*, *a²*, *b*, *c*, and *d*, the cordings *a' b' c' d'*, and the 5 forked strap R, the connectors and the single and double hooked jacks, and means for selecting said jacks, substantially as herein described.

13. The combination, with the loom frame, 10 of the full-stroke lifters 17 and 18 and the half-stroke lifter 55, and means for actuating said lifters, the doup-staff A and the doup-frame B, together provided with the doup *k*, the harness-frames C and D, the cordings *a' b' 15 c' d'* and the forked strap R, the operating-levers *a' a² b c d*, the connectors and the jacks, the jack-selectors and trip-levers therefor, and the pattern-chain 46, substantially as herein described.

14. The combination, as hereinbefore set 20 forth, of full-motion harnesses and means for operating the same, half-and-return-motion harness and doup-staff, and means, substantially as described, for operating said latter harness and doup-staff with half-and-return 25 motions, substantially as described.

15. The combination, as hereinbefore set 30 forth, of full-motion harnesses and means for operating the same, half-and-return-motion harness and doup-staff, and means for operating the said latter harness and doup-staff with half-and-return motions and with full motions, substantially as described.

WM. EVANS.
